US00D934868S

(12) **United States Design Patent** (10) **Patent No.:** **US D934,868 S**
(45) **Date of Patent:** **** Nov. 2, 2021**

(54) **MEMORY CARD**

(71) Applicant: **SONY CORPORATION**, Tokyo (JP)

(72) Inventor: **Akira Kadonaga**, Kanagawa (JP)

(73) Assignee: **SONY CORPORATION**, Tokyo (JP)

(**) Term: **15 Years**

(21) Appl. No.: **29/638,751**

(22) Filed: **Feb. 28, 2018**

(51) LOC (13) Cl. **14-02**

(52) U.S. Cl.

USPC **D14/436**

(58) **Field of Classification Search**

USPC D14/435-438, 478-480; 235/441, 443, 235/487, 492, 493, 495; 361/737, 679, 361/752, 736, 728, 796, 797, 729, 730, 361/725-727; 257/678, 679, 693, 257/E23.064; 439/946, 948, 159; 174/250, 260, 52.1, 52.2; 710/300-303; 438/121

(57)

CLAIM

The ornamental design for a memory card, as shown and described.

DESCRIPTION

FIG. 1 is a perspective view of a memory card showing my new design;

FIG. 2 is a front elevational view thereof; and,

FIG. 3 is a top plan view.

(Continued)

The even-dash broken lines illustrating a portion of the memory card form no part of the claimed design.

1 Claim, 3 Drawing Sheets
